UNITED STATES PATENT OFFICE.

ARTHUR W. LYDA, OF NORTH CANTON, OHIO, ASSIGNEE TO THE AMERICAN SAFETY NAVIGATION COMPANY, OF CANTON, OHIO, A CORPORATION OF OHIO.

DAVIT FOR LIFEBOATS.

Application filed October 12, 1926. Serial No. 141,068.

The invention relates to davits for carrying, raising, and lowering life boats; and the object of the invention is to provide davits comprising curved supporting members extended inward over the deck and arranged to support the life boat in the normal position, boom members being pivoted at their lower ends to the deck and arranged to swing outward on their pivots to lower the life boat, a drum being located in a suitable position adjacent to the davits, preferably beneath the deck, and having a cable wound around the same and extended over pulleys upon each support and boom member and connected to each end of the life boat, suitable motor operating mechanism being provided for revolving the drum, and a brake being provided for controlling the operation of the mechanism, to regulate the speed at which the boat is lowered.

An embodiment of the invention is illustrated in the accompanying drawings, in which

Figure 1 is a side elevation of a life boat provided with the improved davits;

Fig. 2, an end elevation of the same;

Fig. 3, a diagrammatic view showing the movement of one of the swinging booms;

Fig. 4, an enlarged sectional view of the motor driven operating mechanism, taken substantially on the line 4—4, Figs. 5 and 6;

Fig. 5, a vertical section on the line 5—5, Fig. 4;

Fig. 6, a side elevation of the drum and associated mechanism, taken substantially at right angles to Fig. 4;

Fig. 7, a vertical sectional view through the drum, on the line 7—7, Fig. 6;

Fig. 8, an enlarged sectional view through the brake drum, taken substantially on the line 8—8, Fig. 5;

Fig. 9, an enlarged sectional view through the brake cable sheave, on the line 9—9, Fig. 5;

Fig. 10, a section through the drive worm shaft and casing, showing the friction means for preventing reverse movement of the shaft, taken on the line 10—10, Fig. 4, and

Fig. 11, a detail perspective view of one of the blades upon the brake governor.

Similar numerals of reference indicate cor-

responding parts throughout the drawings.

A portion of the deck of a ship is shown at 1, the supporting standards 2 being connected thereto in any suitable manner and properly spaced apart to accommodate the life boat indicated generally at 3.

Each of these supporting standards is preferably curved inward, above the deck and provided at its upper end with a pulley 4 which may be mounted thereon as by the brackets 5.

A base 6 is fixed upon the deck adjacent to each supporting upright and provided with the inverted V-shaped boom member 7, pivoted at its lower end to the base, as indicated at 8, and suitably braced as shown at 9.

Each boom member is arranged to receive the upper portion of the adjacent support when the life boat is in the normal position as shown in Figs. 1 and 2.

A saddle 10 is provided upon each supporting member 2 to receive the trunnion 11, upon the adjacent end of the life boat, and normally support the same, a pivoted latch 12 being provided for engaging the trunnion and holding the boat in position upon the supports.

The lower portion of each latch is pivotally connected at 13 to a link 14 pivoted to 80 one end of the lever 15, which is pivotally mounted upon the adjacent support as shown at 16.

An operating rod 17 is pivotally connected at its inner end to each lever 15 and slidably 85 extended backward through a suitable guide bracket 18, which may be mounted upon the upright cable guiding tube 19.

A plate 20 is carried by the upper end portion of each boom member 7, and provided with a pair of spaced curved tracks 21 and 22, the upper track 21 being of considerably greater length than the lower track.

A pulley 23 is journaled in the upper end of each boom member, and the cable 24, which is passed around or connected to the drum 38, passes upward through the tube 19, over the pulleys 4 and 23, and is provided upon its free end with a hook 26, which preferably is of the quick releasing type shown in my Patent No. 1,582,062, of April 27, 1926, arranged to engage an eye 27 provided

upon the adjacent end portion of the life boat. Any suitable adjusting means 28 may be provided in the cable between the end portion thereof and the hook.

5 A block 29 is rigidly connected to the cable by any suitable and well known means and arranged to be normally received by the curved tracks 21 and 22, upon the plate 20, when the parts are in the normal position.

10 For the purpose of limiting the outward swing of the boom member 7, a chain 30 is connected to a portion of each boom member, and to the upper portion of each adjacent upright support 2, limiting the outward 15 swinging movement of the boom members to the dotted line position shown in Fig. 2.

The action of the block 29 in the curved tracks 21 and 22 is illustrated in the diagrammatic drawing shown in Fig. 3. Thus the 20 cable permits the regulation of the outward and inward movement of the boom.

This movement is illustrated in Fig. 3 in which at A the block 29 is shown resting on the surface of the lower curved track 22. By 25 examining the force diagram shown thereon it will be seen that there is a turning moment on the boom equal to $W \times M'$. This turning moment throws the boom outward, and again referring to the force diagram it is seen that 30 bo is less than ao or in other words the cable pull is $\frac{bo}{ao} \times W$.

At B the block 29 has slid along the surface of the lower curved track 22, as the boom 35 has swung partly outward on its center X. At this point ao is equal to bo , and the block 29 is as likely to be against the surface 22 as the surface 21.

At C, with the boom at the outward limit 40 of its movement the line bo has become greater than ao ; therefore, the cable tension in this position is greater than the load.

The block 29 at this point is entirely clear 45 of the lower curved track 22, and as soon as the block is lowered out of contact with the upper curved track 21 the force diagram changes to od and oa with a resultant oc .

This gives a turning moment on the boom 50 around the pivot X equal to $W \times \frac{oc}{oa} \times M^2$.

This turning moment must be resisted by some device such as the chain 30, forming a self locking device which holds the boom 55 solidly in its outward position.

To raise the load the cable runs over the 60 pulleys 23 and 4 to the drum. As the load is lifted the block 29 strikes the upper curved surface 21. Then sufficient extra power must be supplied to overcome this locking moment.

As the cable continues to be drawn in, the 65 block 29 causes the boom to lift and rotate on its pivot, this rotating movement together with the weight of the life boat causing the block to slide along the surface 21 and moving the surface 22 under the block. As soon

as the line ob becomes shorter than the line oa , the block will leave the surface 22 and slide along to the position shown at A.

A supporting plate 31 is mounted in any suitable location adjacent to the davits, preferably beneath the deck and has secured thereto the depending, truncated cone 32, provided at its upper, or base, end with the ball race 33.

70 A disk 34 is secured to the lower end of the cone as by bolts 35 and provided with the flange 36 having a ball race 37 therein.

The drum 38 is provided with a ball race 39 at its upper end, balls 40 cooperating therewith and with the ball race 33 in the base of 80 the cone.

The worm wheel 41 is connected to the lower reduced end 42 of the drum, as by the bolts 43, and provided with a ball race 44, the balls 45 being mounted between said ball 85 race and the race 36 in the disk 34.

The drum 38 is thus journaled upon the upper and lower ball races to revolve around the cone 32. An annular flange 46 is formed upon the drum 38, midway between the top 90 and bottom thereof, the bevel ring gear 47 being connected thereto as by the bolts 48.

A ring flange 49 is connected to the shoudered portion 50 of the drum, below the flange 46, as by the screws 51. A pair of spaced 95 ring flanges 52 are rotatably mounted upon the drum beneath the ring 49, being supported as by the clamps 53 connected to the lower portion of the drum by the screws 54.

A bracket 55 depends from the lower ring 100 52, the worm 56 being journaled therein and meshing with the worm wheel 41. The worm shaft 57 is provided with squared ends 58 to one of which a wrench or other suitable tool 105 may be applied for adjusting the annular channel rings 52 relative to the drum 38.

The cable 24 from one davit leads to the drum 38 between the flanges 46 and 49 and the end of the other cable 24 leads to the annular channel 52.

110 The motor 59 is provided at its upper side with the feet 60, connected, as by the bolts 61, to the wooden blocks 62 mounted upon the under side of the supporting plate 31.

A pinion 63 is mounted upon the shaft 64 115 of the motor and meshes with a gear 65 upon the shaft 66 journaled in the gear case 67 which is supported upon the under side of the plate 31 as by the bolts 68.

A worm 69 is mounted upon the shaft 66 120 and meshes with a worm wheel 70 carried by the tubular shaft 71 which is journaled in the gear case 67 and upon the shaft 72.

A clutch member 73 is fixed upon the tubular shaft 71 and arranged to be engaged by 125 the clutch member 74 which is slidably keyed upon the shaft 72.

A yoke 75 is provided with pins 76 engaging the annular groove 77 in the slideable clutch member 74, one of said pins being con- 130

nected, as by a link 78, with one end of the bell crank 79 which is pivoted, as at 80, upon the depending bracket 81, suspended from the under side of the supporting plate as by bolts 82.

The lower end of the bell crank is pivotally connected, as at 83, to a link 84, swivelly connected to the disk 116, upon the shaft 85, journaled in the U-shaped bracket 86 suspended from the bearing bracket 87.

A bevel pinion 88 is fixed upon one end of the shaft 72 and meshes with the ring gear 47 upon the drum 38. Upon the other end of the shaft 72 is fixed a gear 89 which meshes 15 with a pinion 90 upon the shaft 91.

This latter shaft is journaled in a bearing 92 upon the double bearing bracket 87 and at one end in a bearing 93 formed upon the side of the gear housing, while the other end is 20 journaled in a bearing 94 upon the depending bearing bracket 95.

The brake drum 96 is fixed upon the bearing bracket 87, as by the bolts 97 and 98, and has mounted therein the two semi-circular brake shoes 99. Right and left screws 100 connect the upper and lower ends of the brake shoes, each screw having one end mounted in a threaded aperture 101, in one of the brake shoes, and in a threaded aperture 102 formed in a threaded thimble 103, which is adjustably mounted in a threaded aperture 104 in the other shoe.

An arm 105 is fixed upon each right and left screw 100 and is connected by a pair of links 35 106 to a collar 107 upon the sleeve 108 which is slidably mounted upon the reduced portion 109 of the shaft 91.

This sleeve is provided with an annular groove 110 in which are located pins 111 carried by the lever 112 which is pivoted at its upper end to the block 113, located upon the under side of the plate 31, the lower end thereof being connected by a rod 114 with the rocker arm 115 upon the shaft 85.

A disk 116 is fixed upon one end of the shaft 85 and provided with a peripheral notch 117 arranged to be engaged by the tooth 118 upon a lever 119 pivoted to the U-frame 86 as at 120 and provided at its free end with 50 a weight 121 to normally hold the tooth 118 in engagement with the periphery of the disk.

A cable or cord 122 is connected to the lever 119 and extends to a convenient location above decks where it may be easily reached for operation. A gear 123 is fixed upon the other end 55 of the shaft 85 and meshes with a pinion 124 upon the countershaft 125.

The pulley 126 is mounted upon the countershaft 125, the cable 127 being connected 60 to said pulley and having its free end extended into the life boat.

As shown in Fig. 9, the pulley 126 is connected to the shaft 125 by means of a coil spring 128. This spring is located within a 65 socket 129, in the interior of the pulley, one

end of the spring being connected to the pulley, as shown at 130, and the other end thereof to the countershaft 125 as shown at 131.

The worm 69 is connected to the shaft 66 in the manner shown in Fig. 10. A disk 132 70 is fastened to the gear housing 67 as by the screws 133 and provided with the central opening 134 of greater diameter than the shaft 66. Inclined notches 135 are formed in this central opening and receive the rollers 75 136 which are normally held in frictional engagement with the shaft by the coil springs 137.

For the purpose of controlling the brake governor automatically, vanes or blades 138 80 are carried upon the arms 105. In the event the lift boat is descending too rapidly these arms will be thrown out, not only by centrifugal action but also by the pressure of the air upon these vanes, causing the brake to be applied 85 and slowing up the action.

Assuming the boat is in the raised position, resting upon the supporting standards, and locked in this position by means of the locking device 12-14-15-17, the operation 90 of lowering the boat is as follows:

The cable 127 is pulled, rocking the pulley 126, and through it the shaft 125. Through the pinion 124 and gear 123, the shaft 85 is rocked and through the arm 84 and bell crank 79, link 78 and yoke 75, the clutch member 74 is disengaged from the clutch member 73, whereby the weight of the boat will cause the same to start on the downward movement.

It is of course understood that the latch 100 12 is released, and that as the booms 7 swing outward to the dotted line position, shown in Fig. 2, the boat will then descend in substantially a straight line from the free ends of the booms.

The brake governor, automatically operated by the arms 105 and vanes 138 will control the speed of descent of the boat. If at any time during the descent of the boat it is desirable to stop the same in transit, it is 110 only necessary to pull still more upon the cable 127, 124, and 123 will further rock the shaft 85, and through the arm 115, link 114, lever 112, sleeve 108, links 106 and arms 105, the brake shoes 99 will be applied to the brake 115 drum 96, stopping the operation of the mechanism.

It is of course understood that when the clutch 74-73 is opened the descent of the boat is caused by the weight of the boat pulling upon the cables 24, rotating the drum 38 and paying out the cables 24.

In raising the boat, the pawl 118 being in engagement with the notch 117 of the disk 116, it is necessary to pull upward upon the cable 122, permitting the spring 128 to turn the shaft 85 to throw in the clutch when the motor may be started to raise the boat.

For emergency use, in the event that the motor is inoperative, for any reason, a gear 130

140 is fixed upon the motor shaft and meshes with a pinion 141 upon the shaft 142, which is journaled in the bracket 143.

5 This shaft is provided with a squared portion 144, adapted to receive a suitable tool by means of which the shaft may be rotated by hand to operate the raising mechanism.

10 The operation of the device is as follows: With the life boat in the normal raised position, resting upon the standards 2, and locked thereon by the latches 12, it is only necessary to release the catches 12 and to pull upon the cable 127, to put the lowering mechanism into operation.

15 This pull upon the cable 127 turns the pulley 126, and through the same rocks the shaft 125. The pinion 124 upon this shaft, co-operating with the gear 123, rocks the shaft 85, and the arm 84 carried thereby operates 20 the bell crank 79, which, through the link 78, and yoke 75, acts to disengage the clutch member 74, from the member 73.

25 The drum 38 being thus released, the weight of the boat, pulling upon the cables 24, will 30 rotate the drum, permitting the boat to descend. The booms 7 will first swing out to the extent of their movement, as limited by the chains 30, this position being shown in dot and dash lines in Fig. 2, after which the 35 boat will descend substantially vertically until it reaches the water.

35 The speed of descent of the boat will be controlled by the brake governor, automatically operated by the arms 105 and vanes 138.

40 If it is desired to stop the boat in transit, during the lowering operation, it is only necessary to pull harder on the cable 127. The shaft 85, through the mechanism above described, will be further rocked, and through 45 the arm 115, link 114, lever 112, sleeve 108, links 106 and arms 105 the brake shoes 99 will be applied to the brake drum 96 stopping the mechanism and holding the boat against further descent until the pull upon 50 the cable 127 is released sufficiently to release the brake.

I claim:

1. Davits for a ship's life boat including supports mounted upon the ship's deck, a boom 55 member pivotally mounted upon the deck adjacent to each support, a pulley upon the upper end of each support, a pulley upon the upper end of each boom member, a drum adjacent to the davits, a cable located over the pulley of each boom member and support and having one end connected to the drum, a life 60 boat suspended from the free ends of the cables, a brake mechanism operatively connected to the drum, means operated by the lowering of the life boat for automatically controlling said brake, a motor for raising the boat, a clutch between the motor and the drum and means for holding the clutch in disengaged position to lower the boat.

65 2. Davits for a ship's life boat including

supports mounted upon the ship's deck, a boom member pivotally mounted upon the deck adjacent to each support, a pulley upon the upper end of each support, a pulley upon the upper end of each boom member, a drum adjacent to the davits, a cable located over the pulley of each boom member and support and having one end connected to the drum, a life boat suspended from the free ends of the cables, a brake mechanism operatively connected to the drum, means operated by the lowering of the life boat for automatically controlling said brake, a motor for raising the boat, a clutch between the motor and the drum and means for holding the clutch in disengaged position to lower the boat and for manually controlling said brake from the life boat.

3. Davits for a ship's life boat including supports mounted upon the ship's deck, a boom member pivotally mounted upon the deck adjacent to each support, a pulley upon the upper end of each support, a pulley upon the upper end of each boom member, a drum adjacent to the davits, a cable located over the pulley of each boom member and support and having one end connected to the drum, a life boat suspended from the free ends of the cables, a brake mechanism operatively connected to the drum, means operated by the lowering of the life boat for automatically controlling said brake, a clutch for normally preventing rotation of the drum and manually operated means for controlling said clutch.

4. Davits for a ship's life boat including supports mounted upon the ship's deck, a boom member pivotally mounted upon the deck adjacent to each support, a pulley upon the upper end of each support, a pulley upon the upper end of each boom member, a drum adjacent to the davits, a cable located over the pulley of each boom member and support and having one end connected to the drum, a life boat suspended from the free ends of the cables, a brake mechanism operatively connected to the drum, means operated by the lowering of the life boat for automatically controlling said brake, a clutch for normally preventing rotation of the drum and manually operated means for controlling said clutch and said brake mechanism.

5. Davits for a ship's life boat including supports mounted upon the ship's deck, a boom member pivotally mounted upon the deck adjacent to each support, a pulley upon the upper end of each support, a pulley upon the upper end of each boom member, a drum adjacent to the davits, a cable located over the pulley of each boom member and support and having one end connected to the drum, a life boat suspended from the free ends of the cables, a brake mechanism operatively connected to the drum, means operated by the lowering of the life boat for automatically controlling said brake, a motor operatively connected to the drum for raising the life

boat, a clutch between the motor and the drum, and means for holding the clutch in disengaged position to lower the boat.

6. Davits for a ship's life boat including
5 supports mounted upon the ship's deck, a
boom member pivotally mounted upon the
deck adjacent to each support, a pulley upon
the upper end of each support, a pulley upon
the upper end of each boom member, a drum
10 adjacent to the davits, a cable located over the
pulley of each boom member and support

and having one end connected to the drum, a
life boat suspended from the free ends of the
cables, a brake mechanism operatively con-
nected to the drum, means operated by the 15
lowering of the life boat for automatically
controlling said brake and means for holding
the brake mechanism inoperative when the
life boat is being raised.

In testimony that I claim the above, I have 20
hereunto subscribed my name.

ARTHUR W. LYDA.
